[57] CLAIM

The ornamental design for a computer generated image for a display panel or screen for controlling or editing image data, as shown and described.

DESCRIPTION

FIG. 1 is a front view of a computer generated image on a display panel and screen;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; FIG. 6 is a front view of a sixth embodiment thereof; FIG. 7 is a front view of a seventh embodiment thereof; FIG. 8 is a front view of an eighth embodiment thereof; FIG. 9 is a front view of a ninth embodiment thereof; FIG. 10 is a front view of a tenth embodiment thereof; FIG. 11 is a front view of an eleventh embodiment thereof; FIG. 12 is a front view of a twelfth embodiment thereof; FIG. 13 is a front view of an thirteenth embodiment thereof; FIG. 14 is a front view of a fourteenth embodiment thereof; FIG. 15 is a front view of a fifteenth embodiment thereof; FIG. 16 is a front view of an sixteenth embodiment thereof; FIG. 17 is a front view of a seventeenth embodiment thereof; FIG. 18 is a front view of an eighteenth embodiment thereof; FIG. 19 is a front view of a nineteenth embodiment thereof; FIG. 20 is a front view of a twentieth embodiment thereof; FIG. 21 is a front view of a twenty-first embodiment thereof; FIG. 22 is a front view of a twenty-second embodiment thereof; FIG. 23 is a front view of a twenty-third embodiment thereof; FIG. 24 is a front view of a twenty-fourth embodiment thereof; FIG. 25 is a front view of a twenty-fifth embodiment thereof; FIG. 26 is a front view of a twenty-sixth embodiment thereof; FIG. 27 is a front view of a twenty-seventh embodiment thereof; FIG. 28 is a front view of a twenty-eight embodiment thereof; FIG. 29 is a front view of a twenty-ninth embodiment thereof; FIG. 30 is a front view of a thirtieth embodiment thereof; FIG. 31 is a front view of a thirty-first embodiment thereof; and, FIG. 32 is a front view of a thirty-second embodiment thereof.

The broken line drawing of a display panel and screen in all views is for illustrative purposes only and forms no part of the claimed design.
